UNITED STATES PATENT OFFICE

FRANK W. HOBART, OF CHELSEA, MASSACHUSETTS

GARMENT SUPPORTER

Application filed May 22, 1930. Serial No. 454,634.

This invention relates to garters or hose supporters, and has particular reference to the means for connecting the same to the tops of hose or stockings, said means consisting of a button-carrying member and a loop or clasp to be engaged with or dis-connected from the button.

The most commonly employed hose supporters at present have pendent button carriers and metal loop-shaped clasp members to cooperate with the buttons in gripping the upper portions of stockings, the button carrier consisting of a doubled strip of flexible fabric. The flexibility of the latter interferes with easy manipulation of the members when applying to use, because the button can easily shift or swing laterally and cause delay in getting it to proper position in the wide upper part of the metal loop before drawing it into the narrow part of said loop.

One of the objects of my invention is to provide hose-connecting members in which tendency of the button to swing away from proper lateral position is reduced to the minimum, thereby facilitating manipulation in use.

Another object is to reduce the cost of such garment supporters, by constructing the pendent button carrier of a single piece of material of single thickness instead of the usual two strips, or a folded or doubled strip of tape.

With said objects in view, the invention consists in the construction and combination of parts substantially as hereinafter described and claimed.

Of the accompanying drawings:

Figure 1 is an elevation of a complete garter constructed according to my invention.

Figure 2 represents a section on line 2—2 of Figure 1, on an enlarged scale.

Figure 3 represents a section on line 3—3 of Figure 1, on an enlarged scale.

Similar reference characters designate similar parts or features in all of the views.

In Figure 1 an ordinary leg-surrounding band is illustrated at 12 and having a suitable pad 13 which is usually of two-ply material as indicated in Figure 2. Secured to

and depending from the pad 13 is a strip 14 of leather or reinforced rubber the upper end of which is split or slotted as at 15, the terminals of the slotted portion being enclosed in and stitched to the two-ply pad 13. Before such stitching is effected however, the upper cross member 16 of the loop-shaped clasp member 17 is placed in said slit 15. Sometimes, although not always necessary, transverse stitches are applied at 18.

The lower end of the strip 14 is also split or slotted at 19 for a sufficient distance inwardly to receive the base plate 20 of a stud 21 on which the button 22 is mounted. Said plate stud and button may be of any well known or preferred structure. Preferably the material of said split end 19 is cemented together, but stitching may be employed for uniting the split parts together.

In operation, connection is made with a stocking in the usual way; but while the flexibility of the leather or rubber strip will permit the button to be slid up to and out through the wider portion of the loop 17, the comparative stiffness of the strip of single thickness material will effect a resistance to the button getting out of proper lateral position.

While the invention is illustrated as embodied in a man's garter, with the usual band to surround the leg of a wearer, it is to be understood that I do not limit myself thereto, as the described members of my invention may be employed in stocking supporters such as those used by women.

Having now described my invention, I claim:

1. A garment supporter having garment-connecting members comprising a button-carrying strip of material having a split upper end, and a button-engaging clasp member hung in said split.

2. A garment supporter having garment-connecting members comprising a button-carrying strip of material having a split upper end, and a button-engaging clasp member having its upper end mounted in said split, the lower end of the split being stitched across.

3. A garment supporter comprising a

single strip of material having slits in its upper and lower ends, a button having its base in the lower slit, and a button-engaging clasp member hung in the upper slit of said strip.

5 In testimony whereof I have affixed my signature.

FRANK W. HOBART.
